SWITCH BOX SECURING DEVICE

Bernard R. Jett, Washington, D. C., assignor of
one-half to Clarence E. Whitmore, Washington, D. C.

Application October 13, 1936, Serial No. 105,431

5 Claims. (Cl. 247—21)

This invention relates to certain improvements in switch box holding or securing means and more particularly to a plate-like device preferably constructed of sheet metal adapted to cooperate with the conventional wall switch box and wall, whereby said switch box may be tightly and rigidly secured to walls of various thicknesses and construction, such as lath and plaster walls, wall board, wood paneling and the like.

10 The usual practice, in new buildings is to leave openings in the walls at the desired locations and provide for the use of bolts or screws to secure the switch boxes in said openings, but this is not entirely satisfactory and sometimes difficult to accomplish without the loss of considerable time in making the necessary adjustments.

This problem becomes even more difficult where switch boxes are to be installed in the walls of old buildings, requiring new openings to be cut 20 in the walls, and generally the character and construction of the wall makes it impossible to use bolts or screws and like fastenings.

The object of the present invention is to provide a quickly adjusted clamping device interposed between the sides of the switch box and the inner face of the wall, whereby said switch box will be automatically locked to the wall by a longitudinal movement of the device irrespective of the thickness or particular construction of the 25 wall and without requiring the use of bolts, nails, screws and the like. At the same time the switch box may be quickly removed when desired without distortion or mutilation and without the use of tools.

30 A further object is the production of a device or devices of the character indicated simple in construction and design and capable of being manufactured on a quantity production basis at a low cost.

35 Another object is the provision of a securing device for wall switch boxes that will automatically adjust itself to walls of various thicknesses and types of construction.

Briefly stated the instant invention comprises 40 preferably a sheet metal member adapted to be inserted along each side of the switch box between said switch box and the adjacent sides of the wall opening, said devices being so shaped as to engage the outer side edges of the switch box 45 and the inner face of the wall at the switch box opening, the peculiar construction of said locking devices producing a wedging or cam action between these parts upon a longitudinal movement of said devices.

50 The preferred embodiment of the invention is

illustrated in the accompanying drawings, in which

Figure 1 is substantially a full size view of one of the securing devices for use in connection with a thin wall;

Figure 2 is a similar view of the securing device altered to adapt the same to a thick wall;

Figure 3 is a plan view illustrating the securing devices in operative position with respect to the switch box and wall;

Figure 4 is a view in side elevation more clearly illustrating the securing devices in operative position in connection with a thick wall;

Figure 5 illustrates the manner of applying the device; and

Figure 6 shows the use of the device in combination with a lath and plaster wall.

Referring to the drawings in detail the improved securing means comprise preferably two sheet metal plates or the like 1, each provided with a transversely extending hook-like extension 2 formed intermediate the ends thereof adjacent a shouldered or recessed portion 3, the horizontal engaging edge surface of the shouldered portion extending to one end of the plate-like devices as clearly shown in Figures 1 and 2.

The opposite end of the device is provided with a sloping or cam-like edge surface 4, terminating in a relatively narrow reduced end portion 5. The opposite end 6 of the device, provided with the shoulder 3, is relatively wide and is constructed with a series of horizontal grooves or the like, producing weakened portions 7 connected by a vertical groove or the like 8, said weakened portion permitting the device to be used in connection with walls of various thicknesses in a manner to be hereinafter more fully described.

Referring to Figure 3 there is shown the conventional or standard switch-box 9, having the usual securing angle clips or ears 10 and the cover plate (not shown) securing extensions 11. The box is shown positioned in the wall 12, the proper opening 13 being provided in the wall to receive the box. This opening is made slightly wider than the box, to receive each side thereof, one of the securing devices 1, the hook-like extensions 2 thereof adapted to engage the opposite side edges of the switch box and the shouldered portion 3 and the cam portion 4 of each device positioned to engage the inner face of the wall, as more clearly shown in Figure 4.

The operation of the device is illustrated in Figure 5 wherein the box 9 is inserted in the opening of the wall 12 with the ears 10 resting against the outer face of said wall. This figure illustrates

a thin wall, which might be either wall board or a panel wall, but it is to be understood that the operation and function of the device is the same in connection with walls of various thicknesses.

- 5 After the box is positioned in the wall opening the securing device 1 is inserted between the side of the switch box and the side of the wall opening, the end 6, having the shouldered portion 3, being first inserted until the hook-like extension 2 is in engagement with the outer edge of the switch box 9 (see Figure 5), and with this point as a fulcrum the end 5 is moved downwardly until the securing device 1 is in a horizontal position, whereupon a forward longitudinal movement of said device will wedge the cam surface 4 into engagement with the inner face of the wall at one end of the box, and the shouldered end portion 3 will also be forced against the inner surface of the wall at the opposite end of the box securely clamping the switch box in position as clearly shown in dotted lines in Figure 5.

It is to be understood that two of these securing devices 1 are used, one on each side of the switch box, and Figures 3 and 4 illustrate clearly the cooperative relation of a pair of said devices in locked or operative position.

As hereinbefore stated the device 1 is adaptable for use in connection with walls of various thicknesses, and this is accomplished by providing said device with the horizontally arranged grooves producing weakened portion 7 (see Figs. 1 and 2) connected by vertical groove 8. On thin walls the device as illustrated in Figures 1 and 5 is used, wherein the end 6 is of full width. On walls of increasing thickness it is only necessary to remove one or more of the weakened portions as illustrated in Figure 2. Figures 4 and 6 show the device as used with thick walls wherein the shoulder portion 3 is relatively deep owing to the removal of a number of the weakened portions of the end 6.

When the device is used in connection with lath and plaster walls, it may be desirable to reverse the ears 10 of the switch box so that said ears may rest on the lath instead of the plaster as shown in Figure 6. This in no way, however, affects the operation of the locking device.

50 In order to obtain possibly a more positive holding of the devices 1 the cam surface 4 may be provided with a rough surface and this rough surface will automatically be produced in the shoulder portion 3 as the weakened portions are removed as illustrated in Figure 2.

What I claim is:

1. A device for securing an outlet box in a wall opening, comprising a substantially flat sheet metal member, a hook-like portion on one side edge of said member for engagement with the outer side edge of said outlet box, a recessed shouldered portion formed on one end of said member for engagement with the inner face of the wall adjacent the wall opening at one end of the box and a cam portion provided on the other end of said member for engagement with the inner edge of the wall opening adjacent the other end of the box, whereby said box will be rigidly

locked in the wall opening upon a longitudinal sliding movement of said member.

2. A device for securing an outlet box in a wall opening, comprising a substantially flat sheet metal member, a hook-like portion on one side edge of said member intermediate the ends thereof for sliding engagement with the outer side edge of said outlet box, a recessed shouldered portion formed on one end of said member for engagement with the inner face of the wall adjacent the wall opening at one end of the box and a cam portion provided on the other end of said member for engagement with the inner edge of the wall opening adjacent the other end of the box, whereby said box will be rigidly locked in the wall opening upon a longitudinal sliding movement of said member.

3. A device for securing an outlet box in a wall opening, comprising a substantially flat sheet metal member, a hook-like portion on one side edge of said member for engagement with the outer side edge of said outlet box, a recessed shouldered portion formed on one end of said member for engagement with the inner face of the wall adjacent the wall opening at one end of the box, said shouldered portion being provided with parallel longitudinal grooves producing removable weakened portions to vary the depth of said shouldered portions and a cam portion provided on the other end of said member for engagement with the inner edge of the wall opening adjacent the other end of the box, whereby said box will be rigidly locked in the wall opening upon a longitudinal sliding movement of said member.

4. A device for securing an outlet box in a wall opening, comprising a substantially flat sheet metal member, a hook-like portion on one side edge of said member for engagement with the outer side edge of said outlet box, a recessed shouldered portion formed on one end of said member for engagement with the inner face of the wall adjacent the wall opening at one end of the box and a cam portion having a rough engaging surface provided on the other end of said member for engagement with the inner edge of the wall opening adjacent the other end of the box, whereby said box will be rigidly locked in the wall opening upon a longitudinal sliding movement of said member.

5. The combination with an outlet box and a wall opening therefor, of a pair of rigid locking members for said box interposed between the side walls of the box and the sides of the opening, a rigid hook-like portion on one side edge of each member for engagement with the respective outer side edges of said outlet box, a recessed shouldered portion formed on one end of each of said members for engagement with the inner face of the wall adjacent the wall opening at one end of the box and a cam portion provided on the other end of each of said members for engagement with the inner edge of the wall opening adjacent the other end of the box, whereby said box will be rigidly wedged into locking engagement with the wall opening upon a longitudinal sliding movement of said members.

BERNARD R. JETT.
